ABSTRACT

A display device includes a pixel array unit in which pixels are arranged, each pixel including a light emitting unit, a writing transistor that writes a video signal, a driving transistor that drives the light emitting unit based on the video signal written by the writing transistor, and a switching transistor that applies a fixed potential to one terminal of the light emitting unit, and a driving unit that causes the light emitting unit to enter a light extinction state by writing a voltage causing the driving transistor to enter a non-conduction state to a gate electrode of the driving transistor.

DISPLAY DEVICE, METHOD OF DRIVING DISPLAY DEVICE AND ELECTRONIC APPARATUS

CROSS REFERENCE TO RELATED APPLICATIONS

This application claims the benefit of Japanese Priority Patent Application JP 2013-215957 filed Oct. 17, 2013, the entire contents of which are incorporated herein by reference.

BACKGROUND

This disclosure relates to a display device, a method of driving the display device, and an electronic apparatus.

In recent years, a flat (flat panel type) display device in which pixels each including a light emitting unit are arranged in a matrix form has become mainstream as a display device. In this type of display device, a driving circuit for driving the light emitting unit may include a driving circuit having a configuration having three transistors (Tr) of a writing transistor that writes a video signal, a driving transistor that drives the light emitting unit, and a switching transistor that applies a fixed potential to a source electrode of the driving transistor (for example, see Japanese Unexamined Patent Application Publication No. 2008-225345).

SUMMARY

In the display device including the driving circuit having the configuration described above, when the switching transistor enters a conduction state, and a fixed potential is applied to the source electrode of the driving transistor, a light extinction period of the light emitting unit starts. However, in the light extinction period of the light emitting unit, since a period of time in which the driving transistor and the switching transistor are in a conduction state together increases, a lot of through current flows from the driving transistor via the switching transistor. As a result, a lot of unutilized power that does not contribute to the emission of the light emitting unit is consumed.

Therefore, it is desirable to provide a display device, a method of driving the display device, and an electronic apparatus having the display device in which a through current flowing from a driving transistor via a switching transistor can be suppressed during a light extinction period of a light emitting unit.

According to an embodiment of the present disclosure, there is provided a display device including a pixel array unit in which pixels are arranged, each pixel including a light emitting unit, a writing transistor that writes a video signal, a driving transistor that drives the light emitting unit based on the video signal written by the writing transistor, and a switching transistor that applies a fixed potential to one terminal of the light emitting unit; and a driving unit that causes the light emitting unit to enter a light extinction state by writing a voltage causing the driving transistor to enter a non-conduction state to a gate electrode of the driving transistor.

Further, according to another embodiment of the present disclosure, there is provided a method of driving a display device in which pixels are arranged, each pixel including a light emitting unit, a writing transistor that writes a video signal, a driving transistor that drives the light emitting unit based on the video signal written by the writing transistor,

and a switching transistor that applies a fixed potential to one terminal of the light emitting unit, in which a voltage causing the driving transistor to enter a non-conduction state is written to a gate electrode of the driving transistor to cause the light emitting unit to enter a light extinction state in driving the display device.

Further, according to still another embodiment of the present disclosure, there is provided an electronic apparatus with a display device including a pixel array unit in which pixels are arranged, each pixel including a light emitting unit, a writing transistor that writes a video signal, a driving transistor that drives the light emitting unit based on the video signal written by the writing transistor, and a switching transistor that applies a fixed potential to one terminal of the light emitting unit; and a driving unit that causes the light emitting unit to enter a light extinction state by writing a voltage causing the driving transistor to enter a non-conduction state to a gate electrode of the driving transistor.

In the display device, the method of driving the display device, or the electronic apparatus that has the configuration described above, the voltage causing the driving transistor to enter a non-conduction state is written to the gate electrode of the driving transistor. Accordingly, the driving transistor enters a non-conduction state, an emission period of the light emitting unit ends, and a light extinction period starts. In other words, the timing of the start of the light extinction period is defined as a timing at which the writing transistor enters a conduction state, not a timing at which the switching transistor enters a conduction state. Also, as the driving transistor enters the non-conduction state, it is possible to suppress a through current flowing from the driving transistor via the switching transistor.

According to the embodiments of the present disclosure, in the light extinction period of the light emitting unit, since the through current flowing from the driving transistor via the switching transistor can be suppressed, it is possible to suppress consumption of unutilized power that does not contribute to the emission of the light emitting unit.

In addition, the present disclosure is not necessarily limited to the effects described herein, and any effect described in the present specification may be obtained. In addition, the effects described in the present specification are only illustrative, the present disclosure is not limited thereto, and there may be additional effects.

BRIEF DESCRIPTION OF THE DRAWINGS

FIG. 1 is a system configuration diagram illustrating a schematic basic configuration of an active matrix display device to which a technology of the present disclosure is applied;

FIG. 2 is a circuit diagram illustrating an example of a specific circuit configuration of a pixel (pixel circuit);

FIG. 3 is a timing waveform diagram illustrating an operation of a method of driving an organic EL display device according to a comparative example;

FIG. 4 is an equivalent circuit diagram of a pixel circuit illustrating an expression of a bootstrap gain G_{bs} ;

FIG. 5 is a timing waveform diagram illustrating an operation of a method of driving an organic EL display device according to Embodiment 1;

FIG. 6 is an equivalent circuit diagram of a pixel circuit illustrating an expression of a writing gain G_{in} ;

FIG. 7 is a timing waveform diagram illustrating an operation of a method of driving an organic EL display device according to Embodiment 2;

FIG. 8 is a timing waveform diagram illustrating an operation of a method of driving an organic EL display device according to Embodiment 3; and

FIG. 9 is a circuit diagram illustrating a modification example of a pixel (pixel circuit).

DETAILED DESCRIPTION OF EMBODIMENTS

Hereinafter, forms of carrying out a technology of the present disclosure (hereinafter referred to as “embodiments”) will be described in detail using the drawings. The technology of the present disclosure is not limited to the embodiments, and various numerical values or the like in the embodiments are illustrative. In the following description, the same elements, or elements having the same function will be denoted with the same reference signs and repeated description will be omitted. In addition, description will be given in the following order.

1. Entire description of a display device, a method of driving the display device, and an electronic apparatus of the present disclosure
2. Display device to which a technology of the present disclosure is applied
  - 2-1. System configuration

5. Electronic apparatus

Entire description of a display device, a method of driving the display device, and an electronic apparatus of the present disclosure

The display device of the present disclosure is a flat (flat panel type) display device in which pixels (pixel circuits) are arranged, each having a configuration in which a driving circuit for driving a light emitting unit includes at least three transistors (Tr) of a writing transistor, a driving transistor, and a switching transistor. Examples of the flat display device may include an organic EL display device, a liquid crystal display device, and a plasma display device. In the organic EL display device among these display devices, electro luminescence (EL) of an organic material is used, and an organic EL element using a phenomenon in which light is emitted when an electric field is applied to an organic thin film is used as a light emitting element (electro-optic element) of the pixel.

The organic EL display device in which the organic EL element is used as a light emitting unit of the pixel has the following features. That is, the organic EL display device has low power consumption since the organic EL element can be driven with applied voltages equal to or lower than 10 V. The organic EL display device has higher image visibility than the liquid crystal display device that is the same flat display device since the organic EL element is a self light emitting element, and is easily made lightweight and thin since an illumination member such as a backlight is not necessary. Further, in the organic EL display device, no afterimage is generated at the time of video display since a response speed of the organic EL element is as very high as about several microseconds.

The organic EL element constituting the light emitting unit is a self light emitting element and is a current-driven electro-optic element whose emission luminance changes according to the value of a current flowing in a device.

Examples of the current-driven electro-optic element may include an inorganic EL element, an LED element, and a semiconductor laser element, as well as the organic EL element.

5 The flat display device, such as the organic EL display device, can be used as a display unit (display device) in various electronic apparatuses with a display unit. Examples of various electronic apparatuses may include a digital camera, a video camera, a game console, a laptop type personal computer, a portable information device such as an electronic book, a personal digital assistant (PDA), or a mobile communication device such as a portable phone.

In the display device, the method of driving the display device, and the electronic apparatus of the present disclosure, each pixel of a pixel array unit can have a configuration having a function of performing correction of a variation in driving current caused by a variation in threshold voltage of a driving transistor (hereinafter referred to also as “threshold correction”). In this case, a voltage causing the driving transistor to enter a non-conduction state can be used as a reference voltage that is used when the threshold correction is performed. In addition, a driving unit can have a configuration for writing the voltage causing the driving transistor to enter a non-conduction state to a holding capacitor.

20 In the display device, the method of driving the display device and the electronic apparatus of the present disclosure including the preferred configuration described above, the driving unit can have a configuration in which a fixed potential is applied to a source of the driving transistor via the switching transistor in a state in which the voltage causing the driving transistor to enter a non-conduction state is written to a gate of the driving transistor. In this case, the driving unit can have a configuration in which, when the switching transistor is in a conduction state, a voltage lower than the voltage causing the driving transistor to enter a non-conduction state is written to the gate of the driving transistor.

25 In addition, in the display device, the method of driving the display device, and the electronic apparatus of the present disclosure including the preferred configuration described above, the threshold voltage of the driving transistor is V_{th_Drv} , and the fixed potential applied to the source of the driving transistor is V_{ss} . In this case, the voltage written to the gate of the driving transistor can be a voltage lower than $(V_{th\_Drv}+V_{ss})$ in a conduction state of the switching transistor.

30 In addition, in the display device, the method of driving the display device, and the electronic apparatus of the present disclosure including the preferred configuration described above, the voltage written to the gate of the driving transistor in the conduction state of the switching transistor can be a voltage lower than a reference voltage that is used when the threshold voltage is corrected. In addition, the driving unit can have a configuration in which the reference voltage that is used when the threshold voltage is corrected and the voltage lower than the reference voltage are written to the gate of the driving transistor via the writing transistor.

35 In addition, in the display device, the method of driving the display device, and the electronic apparatus of the present disclosure including the preferred configuration described above, the threshold voltage of the writing transistor is V_{th_WS} , the threshold voltage of the driving transistor is V_{th_Drv} , and the fixed potential applied to the source of the driving transistor is V_{ss} . Also, the voltage causing the writing transistor to enter a non-conduction state is set to be lower than $(V_{th\_WS}+V_{th\_Drv}+V_{ss})$. In this case, the driving

unit can have a configuration in which a fixed potential is applied to the source of the driving transistor via the switching transistor before the reference voltage that is used when the threshold voltage is corrected is written to the gate of the driving transistor. Display device to which a technology of the present disclosure is applied.

System Configuration

FIG. 1 is a system configuration diagram illustrating a schematic basic configuration of an active matrix display device to which a technology of the present disclosure is applied.

The active matrix display device is a display device in which a current flowing in an electro-optic element is controlled using an active element, such as an insulated gate field effect transistor, provided within the same pixel as a pixel in which the electro-optic element is provided. A thin film transistor (TFT) can be typically used as the insulated gate field effect transistor.

Here, a case of the active matrix organic EL display device in which, for example, an organic EL element that is a current-driven electro-optic element whose emission luminance changes according to the value of a current flowing in a device is used as a light emitting element (light emitting unit) of a pixel (a pixel circuit), will be described by way of example. Hereinafter, the “pixel circuit” may be simply described as a “pixel.”

The organic EL display device 10 of the present disclosure includes a pixel array unit 30 in which a plurality of pixels 20 including organic EL elements are arranged two-dimensionally in a matrix form, and a driving unit (a driving circuit unit) arranged around the pixel array unit 30, as illustrated in FIG. 1. The driving unit includes, for example, a write scanning unit 40, a drive scanning unit 50, and a signal output unit 60 that are mounted on the same display panel 70 as that on which the pixel array unit 30 is mounted, and drives each pixel 20 of the pixel array unit 30. In addition, a configuration in which some or all of the write scanning unit 40, the drive scanning unit 50 and the signal output unit 60 are provided outside the display panel 70 can be adopted.

Here, when the organic EL display device 10 is for a color display, one pixel (unit pixel/pixel) that is a unit for forming a color image includes a plurality of sub-pixels. In this case, each of the sub-pixels corresponds to the pixel 20 of FIG. 1. More specifically, in a display device for a color display, one pixel includes, for example, three sub-pixels including a sub-pixel that emits red (R) light, a sub-pixel that emits green (G) light, and a sub-pixel that emits blue (B) light.

However, one pixel is not limited to a combination of sub-pixels of 3 primary colors of RGB, and can include a sub-pixel of one color or a plurality of colors, in addition to the sub-pixels for 3 primary colors. More specifically, for example, a sub-pixel that emits white (W) light for luminance improvement is added to constitute one pixel, or at least one sub-pixel that emits complementary color light to extend a color reproduction range is added to constitute one pixel.

In the pixel array unit 30, for an arrangement of the pixels 20 of m rows and n columns, a scanning line 31 (31₁ to 31_m) and a driving line 32 (32₁ to 32_m) are wired for each pixel row in a row direction (an arrangement direction of the pixels in a pixel row/a horizontal direction). Further, for the arrangement of the pixels 20 of m rows and n columns, a signal line 33 (33₁ to 33_n) is wired for each pixel column in a column direction (an arrangement direction of the pixels in a pixel column/a vertical direction).

The scanning lines 31₁ to 31_m are connected to respective output ends of corresponding rows of the write scanning unit 40. The driving lines 32₁ to 32_m are connected to respective output ends of corresponding rows of the drive scanning unit 50. The signal lines 33₁ to 33_n are connected to respective output ends of corresponding columns of the signal output unit 60.

The write scanning unit 40 includes, for example, a shift register circuit. This write scanning unit 40 performs so-called line sequential scanning to scan the respective pixels 20 of the pixel array unit 30 in units of rows by sequentially supplying a write scanning signal WS (WS₁ to WS_m) to the scanning line 31 (31₁ to 31_m) when writing a signal voltage of a video signal to the respective pixels 20 of the pixel array unit 30.

The drive scanning unit 50 includes, for example, a shift register circuit, similar to the write scanning unit 40. This drive scanning unit 50 supplies a drive scanning signal AZ (AZ₁ to AZ_m) to the driving line 32 (32₁ to 32_m) in synchronization with the line sequential scanning by the write scanning unit 40.

The signal output unit 60 selectively outputs a signal voltage of a video signal according to luminance information to be supplied from a signal supply source (not illustrated) (hereinafter may be described simply as a “signal voltage”) V_{sig}, and a reference voltage V_{ofs}. Here, the reference voltage V_{ofs} is a voltage that is a reference of the signal voltage V_{sig} of the video signal (for example, a voltage corresponding to a black level of the video signal), and is used at the time of a threshold correction process to be described below.

The signal voltage V_{sig}/the reference voltage V_{ofs} output from the signal output unit 60 is written to each pixel 20 of the pixel array unit 30 via the signal line 33 (33₁ to 33_n) in units of pixel rows selected through the scanning by the write scanning unit 40. In other words, the signal output unit 60 adopts a driving form based on line sequential writing in which the signal voltage V_{sig} is written in units of rows (lines).

Pixel Circuit

FIG. 2 is a circuit diagram illustrating an example of a specific circuit configuration of the pixel (pixel circuit) 20. A light emitting unit of the pixel 20 includes an organic EL element 21 that is a current-driven electro-optic element whose emission luminance changes according to the value of a current flowing in the device.

The pixel 20 includes the organic EL element 21, and a driving circuit that drives the organic EL element 21 by flowing a current to the organic EL element 21, as illustrated in FIG. 2. The organic EL element 21 includes a cathode electrode connected to a common power supply line 34 wired for all the pixels 20 in common. In addition, an equivalent capacitor C_{oled} of the organic EL element 21 is also illustrated in FIG. 2.

The driving circuit that drives the organic EL element 21 has a 3Tr1C configuration in which at least three transistors (Tr) of a driving transistor 22, a writing transistor 23 and a switching transistor 24, and one holding capacitor (C) 25 are included. N channel transistors can be used as the driving transistor 22, the writing transistor 23 and the switching transistor 24. However, a combination of conductivity types of the driving transistor 22, the writing transistor 23 and the switching transistor 24 illustrated herein is only an example and the present disclosure is not limited to the combination thereof.

In the driving transistor 22, a source electrode is connected to an anode electrode of the organic EL element 21,

and a drain electrode is connected to a node for a power supply voltage V_{cc} . In the writing transistor 23, one of source and drain electrodes is connected to the signal line 33 (33₁ to 33_m), and the other electrode is connected to a gate electrode of the driving transistor 22. In addition, a gate electrode of the writing transistor 23 is connected to the scanning line 31 (31₁ to 31_m).

In the switching transistor 24, one of source and drain electrodes is connected to the source electrode of the driving transistor 22 and an anode electrode of the organic EL element 21, and the other electrode is connected to a node for a fixed potential V_{ss} . In addition, the gate electrode of the switching transistor 24 is connected to the driving line 32 (32₁ to 32_m). In the holding capacitor 25, one electrode is connected to the gate electrode of the driving transistor 22, and the other electrode is connected to the source electrode of the driving transistor 22 and the anode electrode of the organic EL element 21.

Here, when a threshold voltage of the organic EL element 21 is V_{th_EL} and a potential of the common power supply line 34, that is, a cathode potential of the organic EL element 21 is V_{cath} , the fixed potential V_{ss} applied to the other electrode of the switching transistor 24 is set to satisfy a relationship of $V_{ss} < V_{cath} + V_{th\_EL}$.

In the pixel 20 having the configuration described above, the writing transistor 23 enters a conduction state in response to the write scanning signal WS whose high voltage state becomes an active state, which is applied from the write scanning unit 40 to the gate electrode via the scanning line 31. Accordingly, the writing transistor 23 writes, to the pixel 20, the signal voltage V_{sig} of the video signal according to luminance information or the reference voltage V_{ofs} supplied from the signal output unit 60 via the signal line 33 at a different timing. The signal voltage V_{sig} or the reference voltage V_{ofs} written by the writing transistor 23 is held in the holding capacitor 25.

The driving transistor 22 operates in a saturation area to supply a driving current having a current value corresponding to the voltage value of the signal voltage V_{sig} held in the holding capacitor 25 to the organic EL element 21 to current-drive the organic EL element 21, so that the organic EL element 21 emits light. The switching transistor 24 enters a conduction state in response to the drive scanning signal AZ whose high voltage state becomes an active state, which is applied from the drive scanning unit 50 to the gate electrode via the driving line 32. Accordingly, the switching transistor 24 applies the fixed potential V_{ss} satisfying the relationship of $V_{ss} < V_{cath} + V_{th\_EL}$ to the source electrode of the driving transistor 22 and the anode electrode of the organic EL element 21. In other words, the switching transistor 24 is a reset transistor that resets a source potential of the driving transistor 22 and an anode potential of the organic EL element 21 to the fixed potential V_{ss} .

Each pixel 20 of the pixel array unit 30 has a function of correcting a variation in driving current caused by a variation in a characteristic of the driving transistor 22. Examples of the characteristic of the driving transistor 22 may include the threshold voltage V_{th} of the driving transistor 22, and mobility u of a semiconductor thin film constituting a channel of the driving transistor 22 (hereinafter referred to simply as "mobility u of the driving transistor 22").

The correction of the variation in driving current caused by the variation in threshold voltage V_{th} (hereinafter referred to also as "threshold correction") is performed by initializing the gate voltage V_g of the driving transistor 22 to be the reference voltage V_{ofs} . Specifically, an operation for changing the source voltage V_s of the driving transistor 22 to be a

potential resulting from subtraction of the threshold voltage V_{th} of the driving transistor 22 from an initialization potential (reference voltage V_{ofs}) of the gate voltage V_g of the driving transistor 22 based on the initialization potential is performed. When this operation progresses, a voltage V_{gs} between the gate and the source of the driving transistor 22 converges into the threshold voltage V_{th} of the driving transistor 22. A voltage corresponding to this threshold voltage V_{th} is held in the holding capacitor 25. Also, since the voltage corresponding to the threshold voltage V_{th} is held in the holding capacitor 25, it is possible to suppress dependence on the threshold voltage V_{th} of a current I_{ds} between the drain and the source that flows in the driving transistor 22 when the driving transistor 22 is driven by the signal voltage V_{sig} of the video signal.

On the other hand, the correction of the variation in the driving current caused by the variation in the mobility u (hereinafter referred to also as "mobility correction") is performed by flowing a current to the holding capacitor 25 via the driving transistor 22 in a state in which the writing transistor 23 enters conduction state and the signal voltage V_{sig} of the video signal is written. In other words, the correction is performed by applying negative feedback to the holding capacitor 25 with a feedback amount (correction amount) corresponding to the current I_{ds} flowing in the driving transistor 22. Through the threshold correction described above, the dependence on the threshold voltage V_{th} of the current I_{ds} between the drain and the source has already been removed when the video signal is written, and the current I_{ds} between the drain and the source depends on the mobility u of the driving transistor 22. Therefore, negative feedback is applied to the voltage V_{ds} between the drain and the source of the driving transistor 22 with a feedback amount according to the current I_{ds} flowing in the driving transistor 22, thus making it possible to suppress the dependence on the mobility u of the current I_{ds} between the drain and the source flowing in the driving transistor 22.

Driving Method According to a Comparative Example

Here, for a method of driving the active matrix organic EL display device 10 having the configuration described above, a technology existing before the technology of the present disclosure (that is, a driving method according to an embodiment) will be briefly described as a method of driving an organic EL display device 10 according to a comparative example using a timing waveform diagram of FIG. 3.

A state of change in each of the potential V_{ofs}/V_{sig} of the signal line 33, the write scanning signal WS, the drive scanning signal AZ, and the gate voltage V_g and the source voltage V_s of the driving transistor 22 are shown in the timing waveform diagram of FIG. 3. In addition, a waveform of the source voltage V_s of the driving transistor 22 is indicated by a dashed line. The potential of the signal line 33 is switched between the reference voltage V_{ofs} and the signal voltage V_{sig} in a 1 horizontal period (1H).

In addition, since the writing transistor 23 and the switching transistor 24 are N channel type transistors, high voltage states of the write scanning signal WS and the drive scanning signal AZ are active states, and low voltage states are inactive states. Also, the writing transistor 23 and the switching transistor 24 enter a conduction state in the active states of the write scanning signal WS and the drive scanning signal AZ, and enter a non-conduction state in the inactive states thereof.

In the timing waveform diagram of FIG. 3, a period up to time t_{01} is an emission period of the organic EL element 21 in a previous display frame. When the time t_{01} arrives, the organic EL element 21 is extinguished, and a light extinction

period (non-emission period) of a new display frame (current display frame) of line sequential scanning starts. Also, a first threshold correction is performed in a period from time t_{03} to time t_{04} , a second threshold correction is performed in a period from time t_{05} to time t_{06} , and writing of the video signal and mobility correction are performed in a period from time t_{07} to time t_{08} .

In the driving method according to the comparative example, the drive scanning signal AZ enters an active state at time t_{01} and thus the switching transistor 24 enters a conduction state. Accordingly, the fixed potential V_{ss} lower than $V_{cath} + V_{th\_EL}$ is written to the anode electrode of the organic EL element 21 (the source electrode of the driving transistor 22) by the switching transistor 24, thus extinguishing the organic EL element 21.

Here, a ratio of a change amount ΔV_g of the gate voltage V_g to a change amount ΔV_s of the source voltage V_s of the driving transistor 22 (hereinafter referred to as a bootstrap gain G_{bst}) is considered. A capacitance value of a parasitic capacitor between the gate electrode and the source electrode of the driving transistor 22 is C_{gs} , a capacitance value of a parasitic capacitor between the gate electrode and the drain electrode is C_{gd} , and a capacitance value of a parasitic capacitor between the gate electrode and the other electrode (the electrode on the driving transistor 22 side) of the writing transistor 23 is C_{ws} , as illustrated in FIG. 4. In addition, a capacitance value of the holding capacitor 25 is C_s .

In this case, the bootstrap gain G_{bst} can be expressed as:

$$\begin{aligned} G_{bst} &= \Delta V_g / \Delta V_s \\ &= (C_s + C_{gs}) / (C_s + C_{ws} + C_{gd} + C_{gs}) \end{aligned} \quad (1)$$

In Expression (1), since the respective capacitance values C_{ws} , C_{gd} and C_{gs} of the parasitic capacitors are sufficiently smaller than capacitance value C_s of the holding capacitor 25, the bootstrap gain G_{bst} generally has a value close to 1.

Here, in the driving method according to the comparative example, a configuration in which the switching transistor 24 enters a conduction state, the fixed potential V_{ss} is applied to the source electrode of the driving transistor 22, and thus a light extinction period of the organic EL element 21 arrives is adopted. However, in the light extinction period of the organic EL element 21, since a period of time in which the driving transistor 22 and the switching transistor 24 enter a conduction state together increases, a lot of through current flows from the driving transistor 22 via the switching transistor 24. As a result, a lot of unutilized power that does not contribute to the light emission of the organic EL element 21 is consumed.

Description of Embodiments

In the driving method according to the comparative example, a timing of the start of the light extinction period (end of the emission period) is defined as a timing at which the drive scanning signal AZ for driving the switching transistor 24 enters an active state, that is, a timing at which the fixed potential V_{ss} is written to the source electrode of the driving transistor 22. In contrast, in the embodiment of the present disclosure, the timing of the start of the light extinction period (end of the emission period) is defined as a timing to write a voltage causing the driving transistor 22 to enter a non-conduction state to the gate electrode of the driving transistor 22.

More specifically, in the present embodiment, the write scanning signal WS enters an active state so that the writing transistor 23 enters a conduction state, and the voltage causing the driving transistor 22 to enter a non-conduction state is written to the gate electrode of the driving transistor 22 so that the organic EL element 21 enters a light extinction state. The reference voltage V_{ofs} that is used when the threshold voltage of the driving transistor 22 is corrected may be used as the voltage causing the driving transistor 22 to enter a non-conduction state. However, this is an example and the present disclosure is not limited to the reference voltage V_{ofs} .

When the voltage causing the driving transistor 22 to enter a non-conduction state is written to the gate electrode of the driving transistor 22, the driving transistor 22 enters a non-conduction state, the emission period of the organic EL element 21 ends, and the light extinction period arrives. In other words, the timing of start of the light extinction period (end of the emission period) is defined as a timing at which the writing transistor 23 enters a conduction state, that is, the write scanning signal WS enters an active state, which is not a time at which the switching transistor 24 enters a conduction state, that is, the drive scanning signal AZ enters an active state.

Also, when the light extinction period arrives, the driving transistor 22 enters a non-conduction state, and thus a through current does not flow from the driving transistor 22 to the node for a fixed potential V_{ss} via the switching transistor 24. Therefore, in the light extinction period, the through current to the node for a fixed potential V_{ss} via the switching transistor 24 can be suppressed, and thus it is possible to suppress consumption of unutilized power that does not contribute to the light emission of the organic EL element 21.

Hereinafter, a specific embodiment for suppressing a through current flowing from the driving transistor 22 to the node for a fixed potential V_{ss} via the switching transistor 24 in a light extinction period will be described.

Embodiment 1

A method of driving an organic EL display device 10 according to Embodiment 1 will be described using a timing waveform diagram of FIG. 5.

A state of change in each of the potential V_{ofs}/V_{sig} of the signal line 33, the write scanning signal WS, the drive scanning signal AZ, and a gate voltage V_g and a source voltage V_s of the driving transistor 22 is illustrated in the timing waveform diagram of FIG. 5. In addition, the waveform of the source voltage V_s of the driving transistor 22 is indicated by a dashed line. The potential of the signal line 33 is switched between the reference voltage V_{ofs} and the signal voltage V_{sig} in a 1 horizontal period (1H).

In addition, since the writing transistor 23 and the switching transistor 24 are N channel type transistors, a high voltage state of the write scanning signal WS and the drive scanning signal AZ becomes an active state, and a low voltage state thereof becomes an inactive state, as in the case of the driving method according to the comparative example. Also, the writing transistor 23 and the switching transistor 24 enter a conduction state in an active state of the write scanning signal WS and the drive scanning signal AZ, and enter a non-conduction state in an inactive state thereof. The same applies to Embodiments 2 and 3.

In the timing waveform diagram of FIG. 5, a period up to t_{11} is an emission period of the organic EL element 21 in a previous display frame. When t_{11} arrives, the write scanning

11

signal WS enters an active state and the writing transistor 23 enters a conduction state. In this case, the reference voltage V_{ofs} that is used at the time of threshold correction is supplied from the signal output unit 60 to the signal line 33. Therefore, the writing transistor 23 writes the reference voltage V_{ofs} to the gate electrode of the driving transistor 22 as a voltage causing the driving transistor 22 to enter a non-conduction state.

Here, the reference voltage V_{ofs} is a voltage that is a reference of the signal voltage V_{sig} of the video signal, such as a voltage corresponding to the black level of the video signal. In other words, the reference voltage V_{ofs} is the voltage causing the driving transistor 22 to enter a non-conduction state. Therefore, when the reference voltage V_{ofs} is written to the gate electrode of the driving transistor 22, the driving transistor 22 enters a non-conduction state and supply of a current to the organic EL element 21 stops, thereby extinguishing the organic EL element 21. Also, a light extinction period (non-emission period) of a new display frame (current display frame) of the line sequential scanning arrives. In this case, the drive scanning signal AZ for driving the switching transistor 24 is in the inactive state. Here, the reference voltage V_{ofs} can also be set to the same voltage as the cathode potential V_{cath} of the organic EL element 21.

In the light extinction period, the drive scanning signal AZ enters an active state at time t_{12} at which the write scanning signal WS is in the active state again. In response thereto, the switching transistor 24 enters a conduction state and the fixed potential V_{ss} is written to the source electrode of the driving transistor 22. Accordingly, since the source voltage V_s of the driving transistor 22 is the fixed potential V_{ss} in a state in which the gate voltage V_g of the driving transistor 22 is the reference voltage V_{ofs} , the voltage V_{gs} between the gate and the source of the driving transistor 22 is $V_{ofs} - V_{ss}$. When the voltage V_{gs} between the gate and the source of the driving transistor 22 is not higher than the threshold voltage V_{th} of the driving transistor 22, it is difficult to perform the threshold correction process and thus, the fixed potential V_{ss} is set to satisfy a potential relationship of $V_{ofs} - V_{ss} > V_{th}$.

Thus, the process of fixing the gate voltage V_g of the driving transistor 22 to the reference voltage V_{ofs} and fixing (settling) the source voltage V_s to the fixed potential V_{ss} for initialization is a process of preparation before the threshold correction process (threshold correction operation) is performed (threshold correction preparation). Therefore, the reference voltage V_{ofs} and the fixed potential V_{ss} become respective initialization voltages of the gate voltage V_g and the source voltage V_s of the driving transistor 22. Also, a period from time t_{13} at which the write scanning signal WS enters an inactive state to time t_{14} at which the write scanning signal WS enters an active state again is a threshold correction preparation period.

Then, at time t_{15} , when the drive scanning signal AZ enters the inactive state and the switching transistor 24 enters a non-conduction state, the threshold correction process starts in a state in which the gate voltage V_g of the driving transistor 22 is held at the reference voltage V_{ofs} . In other words, the source voltage V_s of the driving transistor 22 starts to increase to a voltage resulting from subtraction of the threshold voltage V_{th} of the driving transistor 22 from the gate voltage V_g . A period from time t_{15} to time t_{16} at which the write scanning signal WS enters an inactive state is a first threshold correction period. A second threshold correction process is then performed in a period from t_{17} at which the write scanning signal WS enters an active state to time t_{18} .

12

When the threshold correction process progresses, the voltage V_{gs} between the gate and the source of the driving transistor 22 converges into the threshold voltage V_{th} of the driving transistor 22. A voltage corresponding to this threshold voltage V_{th} is held in the holding capacitor 25. In addition, during a period in which the threshold correction process is performed (a threshold correction period), a potential of the common power supply line 34, that is, the cathode potential V_{cath} is set so that the organic EL element 21 enters a cut-off state, in order for a current to flow to only the holding capacitor 25 and not to flow to the organic EL element 21.

Then, at time t_{19} , the write scanning signal WS enters an active state in a state in which the signal voltage V_{sig} of the video signal has been supplied from the signal output unit 60 to the signal line 33. In response thereto, the writing transistor 23 enters a conduction state, and thus the signal voltage V_{sig} of the video signal is sampled and written to the gate electrode of the driving transistor 22. As the signal voltage V_{sig} is written by the writing transistor 23, the gate voltage V_g of the driving transistor 22 becomes a signal voltage V_{sig} . Also, when the driving transistor 22 is driven by the signal voltage V_{sig} of the video signal, the threshold voltage V_{th} of the driving transistor 22 is offset by a voltage corresponding to the threshold voltage V_{th} held in the holding capacitor 25, thus suppressing dependence on the threshold voltage V_{th} of the current I_{ds} between the drain and the source flowing in the driving transistor 22.

In this case, a current (current I_{ds} between the drain and the source) flowing from a node for the power supply voltage V_{cc} to the driving transistor 22 according to the signal voltage V_{sig} of the video signal flows to the equivalent capacitor C_{oled} of the organic EL element 21. Accordingly, charge of the equivalent capacitor C_{oled} of the organic EL element 21 starts.

The source voltage V_s of the driving transistor 22 increases over time due to the charge of the equivalent capacitor C_{oled} of the organic EL element 21. In this case, a variation in driving current caused by a variation in the threshold voltage V_{th} of the driving transistor 22 of each pixel has already been corrected, and the current I_{ds} between the drain and the source of the driving transistor 22 depends on the mobility u of the driving transistor 22.

Here, when it is assumed that a ratio of a change amount ΔV_s of the source voltage V_s of the driving transistor 22 to a change amount ΔV_g of the gate voltage V_g (hereinafter referred to as a writing gain G_{in}) is 0 (ideal value), the source voltage V_s of the driving transistor 22 increases by ΔV , and thus the voltage V_g between the gate and the source of the driving transistor 22 is $V_{sig} - V_{ofs} + V_{th} - \Delta V$.

In other words, the amount of increase ΔV of the source voltage V_s of the driving transistor 22 acts so as to be subtracted from the voltage $(V_{sig} - V_{ofs} + V_{th})$ held in the holding capacitor 25, that is, so that charged charges of the holding capacitor 25 are discharged. In other words, the increase amount ΔV of the source voltage V_s is negative feedback applied to the holding capacitor 25. Therefore, the increase amount ΔV of the source voltage V_s becomes a feedback amount of the negative feedback.

Thus, the negative feedback is applied to the holding capacitor 25 with the feedback amount ΔV according to the current I_{ds} between the drain and the source flowing to the driving transistor 22, thus suppressing dependence on the mobility u of the current I_{ds} between the drain and the source of the driving transistor 22. This process of suppressing the dependence is a mobility correction process of correcting the

variation in the driving current caused by the variation in the mobility u of the driving transistor **22** for each pixel.

More specifically, since the current I_{ds} between the drain and the source increases as a signal amplitude V_{in} ($=V_{sig} - V_{ofs}$) of the video signal written to the gate electrode of the driving transistor **22** becomes higher, an absolute value of the feedback amount ΔV of the negative feedback increases. Therefore, a mobility correction process is performed according to a signal amplitude V_{in} of the video signal, that is, an emission luminance level. In addition, when the signal amplitude V_{in} of the video signal is constant, the absolute value of the feedback amount ΔV of the negative feedback increases as the mobility u of the driving transistor **22** increases, thereby suppressing the variation in the driving current caused by the variation in the mobility u for each pixel.

Then, at time t_{20} , the write scanning signal WS enters an inactive state and the writing transistor **23** enters a non-conduction state in response thereto, thereby electrically disconnecting the gate electrode of the driving transistor **22** from the signal line **33** to enter a floating state. Here, when the gate electrode of the driving transistor **22** is in the floating state, the gate voltage V_g of the driving transistor **22** changes in conjunction with a change in the source voltage V_s due to the holding capacitor **25** being connected between the gate and the source of the driving transistor **22**. Thus, the operation in which the gate voltage V_g of the driving transistor **22** changes in conjunction with the change in the source voltage V_s is a bootstrap operation.

The gate electrode of the driving transistor **22** enters the floating state and, at the same time, the current I_{ds} between the drain and the source of the driving transistor **22** begins to flow to the organic EL element **21**, thereby increasing the anode voltage of the organic EL element **21** according to the current I_{ds} . Also, when the anode voltage of the organic EL element **21** exceeds $V_{th\_EL} + V_{cath}$, the driving current begins to flow to the organic EL element **21** and thus the organic EL element **21** starts to emit light.

In addition, an increase in the anode voltage of the organic EL element **21** is nothing but an increase in the source voltage V_s of the driving transistor **22**. Also, if the source voltage V_s of the driving transistor **22** increases, the gate voltage V_g of the driving transistor **22** also increases in conjunction with the increase in the source voltage due to the bootstrap operation. In this case, if the bootstrap gain G_{bst} is assumed to be 1 (ideal value), the increase amount of the gate voltage V_g is equal to an increase amount of the source voltage V_s . Thus, in the emission period, the voltage V_{gs} between the gate and the source of the driving transistor **22** is maintained to be constant at $V_{sig} - V_{ofs} + V_{th} - \Delta V$.

In the series of operations described above, in the method of driving the organic EL display device **10** according to Embodiment 1, the timing of start of the light extinction period (end of the emission period) is defined as a timing to write the voltage causing the driving transistor **22** to enter a non-conduction state, such as the reference voltage V_{ofs} , to the gate electrode of the driving transistor **22**. In Embodiment 1, a timing to write the reference voltage V_{ofs} may be a timing at which the write scanning signal WS for driving the writing transistor **23** enters an active state.

As illustrated in FIG. 6, a capacitance value of the parasitic capacitor between the gate electrode and the source electrode of the driving transistor **22** is C_{gs} , a capacitance value of the holding capacitor **25** is C_s , and a capacitance value of the equivalent capacitance of the organic EL element **21** is C_{oled} . In this case, the ratio of a change amount ΔV_s of the source voltage V_s to a change amount ΔV_g of the

gate voltage V_g of the driving transistor **22**, that is, a writing gain G_{in} is expressed as Expression (2) below.

$$G_{in} = \Delta V_s / \Delta V_g \quad (2)$$

$$= (C_s + C_{gs}) / (C_s + C_{gs} + C_{oled})$$

Here, if $G_{in} \approx 0$ from $C_{oled} \gg C_s$ and $C_{oled} \gg C_{gs}$, when the reference voltage V_{ofs} is set to a voltage lower than $V_{th\_EL} + V_{cath} + V_{th\_Drv}$ or when the reference voltage V_{ofs} is set to a voltage equal to or lower than V_{cath} , the reference voltage V_{ofs} is written to the gate electrode of the driving transistor **22** at the time of start of the light extinction period (at the time of end of the emission period) and thus the voltage V_{gs} between the gate and the source of the driving transistor **22** is lower than the threshold voltage V_{th_Drv} of the driving transistor **22**. Accordingly, the driving transistor **22** enters a non-conduction state. In this case, the switching transistor **24** also enters a non-conduction state. Therefore, a current (through current) does not flow from the driving transistor **22** to the node for a fixed potential V_{ss} via the switching transistor **24**. Accordingly, in the light extinction period other than the threshold correction preparation period (from time t_{13} to time t_{14}), the through current flowing from the driving transistor **22** to the node for a fixed potential V_{ss} via the switching transistor **24** can be suppressed and thus consumption of unutilized power that does not contribute to the emission of the organic EL element **21** can be suppressed.

Embodiment 2

35 A method of driving an organic EL display device **10** according to Embodiment 2 will be described using a timing waveform diagram of FIG. 7.

40 A state of change in each of the potential $V_{ofs1}/V_{ofs2}/V_{sig}$ of the signal line **33**, the write scanning signal WS, the drive scanning signal AZ, and the gate voltage V_g and the source voltage V_s of the driving transistor **22** is shown in the timing waveform diagram of FIG. 7. In addition, a waveform of the source voltage V_s of the driving transistor **22** is indicated by a dashed line.

45 In Embodiment 2, the following configuration is adopted, in addition to definition of the timing of the start of the light extinction period as the timing at which the voltage causing the driving transistor **22** to enter a non-conduction state is written to the gate electrode of the driving transistor **22**, as in Embodiment 1. That is, in Embodiment 2, a configuration in which a voltage lower than the voltage causing the driving transistor **22** to enter a non-conduction state is written to the gate electrode of the driving transistor **22** when the switching transistor **24** is in a conduction state is adopted.

50 Here, the threshold voltage V_{th} of the driving transistor **22** is V_{th_Drv} . In this case, a voltage written to the gate electrode of the driving transistor **22** in the conduction state of the switching transistor **24** is a voltage lower than $(V_{th\_Drv} + V_{ss})$.

55 In Embodiment 2, a reference voltage V_{ofs} is used as the voltage causing the driving transistor **22** to enter a non-conduction state, as in Embodiment 1. Therefore, the voltage written to the gate electrode of the driving transistor **22** in the conduction state of the switching transistor **24** is a voltage lower than the reference voltage V_{ofs} . Hereinafter, the reference voltage V_{ofs} is V_{ofs1} and the voltage lower than the reference voltage V_{ofs} is V_{ofs2} .

Even in Embodiment 2, the reference voltage V_{ofs2} is assumed to be supplied from the signal output unit 60 via the signal line 33 like the reference voltage V_{ofs1} . Accordingly, a potential of the signal line 33 takes 3 values of the reference voltage V_{ofs1} /the reference voltage V_{ofs2} /the signal voltage V_{sig} of the video signal. Also, the reference voltage V_{ofs1} /the reference voltage V_{ofs2} /the signal voltage V_{sig} are written to the gate electrode of the driving transistor 22 by the writing transistor 23.

In addition, here, the reference voltage V_{ofs2} output from the signal output unit 60 is used as the voltage to be written to the gate electrode of the driving transistor 22 in the conduction state of the switching transistor 24, but the present disclosure is not limited thereto. For example, the fixed potential V_{ss} can also be used as the voltage to be written to the gate electrode of the driving transistor 22 in the conduction state of the switching transistor 24 as long as the threshold voltage V_{th_Drv} of the driving transistor 22 is $V_{th\_Drv} > 0$. The use of the fixed potential V_{ss} makes it unnecessary to separately generate the reference voltage V_{ofs2} , and thus there is an advantage that the use of the fixed potential is advantageous in achieving the simplification of the system.

In a concrete operation of Embodiment 2, a timing of the start of the light extinction period (end of the emission period) is defined as a timing (time t_{11}) to write the reference voltage V_{ofs1} to the gate electrode of the driving transistor 22, as in Embodiment 1. Also, the potential of the signal line 33 is switched from the reference voltage V_{ofs1} to the reference voltage V_{ofs2} at time t_{21} in the active period of the write scanning signal WS, as illustrated in the timing waveform diagram of FIG. 7. With this, the gate voltage V_g and the source voltage V_s of the driving transistor 22 decrease.

In the light extinction period, the drive scanning signal AZ enters an active state at time t_{12} in which the write scanning signal WS is in the active state again. In response thereto, the switching transistor 24 enters a conduction state and writes the fixed potential V_{ss} to the source electrode of the driving transistor 22. Accordingly, initialization of the gate voltage V_g and source voltage V_s of the driving transistor 22 is performed and a threshold correction preparation period arrives.

Then, the potential of the signal line 33 is switched from the reference voltage V_{ofs1} to the reference voltage V_{ofs2} at time t_{22} in a period in which the drive scanning signal AZ is in an active state, that is, a period when the switching transistor 24 is in a conduction state. Accordingly, the reference voltage V_{ofs2} is sampled by the writing transistor 23 and written to the gate electrode of the driving transistor 22. Then, in threshold correction, the write scanning signal WS enters an active state again at time t_{14} . In response thereto, the writing transistor 23 enters a conduction state, and thus the reference voltage V_{ofs1} is written to the gate electrode of the driving transistor 22. Basically, a subsequent operation of first threshold correction, second threshold correction, and signal writing and mobility correction is performed as in Embodiment 1.

As described above, in Embodiment 2, the potential of the signal line 33 has 3 values of the reference voltage V_{ofs1} /the reference voltage V_{ofs2} /the signal voltage V_{sig} . Also, in the threshold correction preparation period, the reference voltage V_{ofs2} satisfying the conditions of $V_{ofs2} < V_{ofs1}$ and $V_{ofs2} - V_{ss} < V_{th\_Drv}$ is written to the gate electrode of the driving transistor 22. Since this driving makes the voltage V_{gs} between the gate and the source of the driving transistor 22 lower than the threshold voltage V_{th_Drv} it is possible to suppress the through current flowing to the node for a fixed

potential V_{ss} via the switching transistor 24 in the light extinction period other than the threshold correction period, that is, the threshold correction preparation period.

Embodiment 3

A method of driving an organic EL display device 10 according to Embodiment 3 will be described using a timing waveform diagram of FIG. 8.

A state of change in each of the potential V_{ofs}/V_{sig} of the signal line 33, the write scanning signal WS, the drive scanning signal AZ and the gate voltage V_g and the source voltage V_s of the driving transistor 22 is shown in a timing waveform diagram of FIG. 8. In addition, a waveform of the source voltage V_s of the driving transistor 22 is indicated by a dashed line.

In Embodiments 1 and 2, a configuration in which the active period of the write scanning signal WS and the active period of the drive scanning signal AZ are overlapped before and after the threshold correction preparation period has been adopted. In contrast, in Embodiment 3, a configuration in which the active period of the write scanning signal WS and the active period of the drive scanning signal AZ are not overlapped in the threshold correction preparation period and before and after the period is adopted.

Also, in Embodiment 3, the voltage causing the writing transistor 23 to enter a non-conduction state, that is, a low voltage WS_L of the write scanning signal WS is set to satisfy Expression (3) below. In other words, when the threshold voltage of the writing transistor 23 is V_{th_WS} and the threshold voltage of the driving transistor 22 is V_{th_Drv} , the voltage WS_L causing the writing transistor 23 to enter a non-conduction state is set to a voltage satisfying:

$$WS\_L < V_{th\_WS} + V_{th\_Drv} + V_{ss} \quad (3)$$

Here, a reason for setting the voltage causing the writing transistor 23 to enter a non-conduction state, that is, the low voltage WS_L of the write scanning signal WS to the voltage satisfying Expression (3) will be described.

In Embodiment 3, a configuration in which the active period of the write scanning signal WS and the active period of the drive scanning signal AZ are not overlapped in the threshold correction preparation period and before and after the period is adopted, as described above. Accordingly, as illustrated in the timing waveform diagram of FIG. 8, at time t_{12} , the drive scanning signal AZ enters an active state, the switching transistor 24 enters a conduction state in response thereto, and thus the fixed potential V_{ss} is written to the source electrode of the driving transistor 22. Then, the gate voltage V_g of the driving transistor 22 is greatly decreased according to a bootstrap gain G_{bst1} due to capacitive coupling. In this case, the voltage V_{gs} between the gate and the source of the driving transistor 22 is likely to be higher than the threshold voltage V_{th_Drv} in accordance with the low voltage WS_L of the write scanning signal WS, and the driving transistor 22 is likely to enter a conduction state.

In the threshold correction preparation period, if the driving transistor 22 enters a conduction state, a through current flows to the node for a fixed potential V_{ss} via the switching transistor 24, and the gate electrode and the source electrode of the driving transistor 22 enter a floating state together from time t_{14} at which the drive scanning signal AZ enters an inactive state to time t_{15} at which the first threshold correction starts. Then, the voltage V_{gs} between the gate and the source of the driving transistor 22 at the time of threshold correction is compressed relative to the threshold voltage V_{th_Drv} through the bootstrap operation, and the correction is

not likely to be applied. Thus, it is necessary to set the low voltage WS_{-L} of the write scanning signal WS to a voltage satisfying Expression (3).

Expression (3) is derived as follows. That is, in the threshold correction preparation period, the voltage V_{gs} between the gate and the source of the driving transistor 22 may satisfy $V_{gs} < V_{th_Drv}$ that is, $V_g - V_{ss} < V_{th_Drv}$.

$WS_{-L} - V_{th_{WS}} - V_{ss_{Drv}}$ is derived from $V_g = WE_{-L} - V_{th_{WS}}$. Thus, the low voltage WS_{-L} of the write scanning signal WS may satisfy Expression (3).

As described above, in Embodiment 3, in the threshold correction preparation period and before and after the period, the low voltage WS_{-L} of the write scanning signal WS is set to the voltage satisfying Expression (3) without overlap of the active period of the write scanning signal WS and the active period of the drive scanning signal AZ. Also, the fixed potential V_{ss} is applied to the source electrode of the driving transistor 22 via the switching transistor 24 before the reference voltage V_{ofs} is written to the gate electrode of the driving transistor 22. Through this driving, the through current does not flow from the driving transistor 22 to the node for a fixed potential V_{ss} via the switching transistor 24, and the through current theoretically is not generated.

Modification Example

While the technology of the present disclosure has been described above using the embodiments, the technology of the present disclosure is not limited to the range described in the embodiments described above. In other words, a variety of modifications or improvements can be made to the embodiments described above without departing from the gist of the technology of the present disclosure, and forms to which such modifications or the improvements have been made are included in the technical range of the technology of the present disclosure.

For example, while the driving circuit for driving the organic EL element 21 has a 3Tr/1C type circuit configuration in which three transistors 22, 23 and 24 and one capacitor 25 are included in the embodiment described above, the present disclosure is not limited thereto. The driving circuit can also have a 3Tr/2C type circuit configuration in which an auxiliary capacitor having one electrode connected to the anode electrode of the organic EL element 21 and the other electrode connected to the node for a fixed potential is added, as necessary, in order to compensate for the insufficient capacitance of the organic EL element 21 and increase a gain for writing a video signal to the holding capacitor 25.

In addition, the driving circuit can also have a 4Tr/1C type circuit configuration in which a switching transistor 26 that selectively applies the reference voltage V_{ofs} to be used for threshold correction to the gate electrode of the driving transistor 22 is added, as illustrated in FIG. 9, or a 4Tr/2C type circuit configuration in which the auxiliary capacitor is further added. The driving circuit can also have a circuit configuration in which a constituent element such as a transistor is further added, as necessary.

Further, while an example in which the present disclosure is applied to the organic EL display device using the organic EL element as the electro-optic element of the pixel 20 has been described in the embodiments described above, the present disclosure is not limited to this application example. Specifically, the technology of the present disclosure is applicable to all display devices using a current-driven electro-optic element whose emission luminance changes

according to a current value flowing in the device, such as an inorganic EL element, an LED element, and a semiconductor laser element.

Electronic Apparatus

5 The display device of the present disclosure described above can be used as a display unit (display device) for electronic apparatuses in all fields in which a video signal input to the electronic apparatus or a video signal generated in the electronic apparatus is displayed as an image or a 10 video.

As apparent from the description of the embodiments described above, since the display device of the present disclosure can suppress the through current flowing to the node for a fixed potential V_{ss} via the switching transistor 24 15 in the light extinction period, it is possible to suppress consumption of unutilized power that does not contribute to the light emission of the organic EL element 21. Therefore, in electronic apparatuses in all fields, the display device of the present disclosure is used as a display unit for the 20 electronic apparatuses, thus contributing to low power consumption by the electronic apparatus.

Examples of the electronic apparatus using the display device of the present disclosure as a display unit may include a digital camera, a video camera, a game device, and a laptop 25 type personal computer, in addition to a television system. In addition, the display device of the present disclosure can also be used as a display unit for an electronic apparatus, including a portable information device such as an electronic book device or an electronic watch, or a portable communication device such as a portable phone or a PDA.

In addition, the present disclosure can take the following 30 configurations.

[1] A display device including a pixel array unit in which pixels are arranged, each pixel including a light emitting 35 unit, a writing transistor that writes a video signal, a driving transistor that drives the light emitting unit based on the video signal written by the writing transistor, and a switching transistor that applies a fixed potential to one terminal of the light emitting unit; and a driving unit that causes the light 40 emitting unit to enter a light extinction state by writing a voltage causing the driving transistor to enter a non-conduction state to a gate electrode of the driving transistor.

[2] The display device according to [1], wherein each 45 pixel of the pixel array unit has a function of correcting a threshold voltage of the driving transistor.

[3] The display device according to [2], wherein the voltage causing the driving transistor to enter a non-conduction state is a reference voltage that is used when a threshold voltage is corrected.

[4] The display device according to [2] or [3], wherein the driving unit writes the voltage causing the driving transistor to enter a non-conduction state to a holding capacitor.

[5] The display device according to any one of [1] to [4], wherein the driving unit applies a fixed potential to a source 55 electrode of the driving transistor via the switching transistor in a state in which the voltage causing the driving transistor to enter a non-conduction state is written to the gate electrode of the driving transistor.

[6] The display device according to [5], wherein the driving unit writes a voltage lower than the voltage causing the driving transistor to enter a non-conduction state to the gate electrode of the driving transistor when the switching transistor is in a conduction state.

[7] The display device according to [6], wherein, when a threshold voltage of the driving transistor is V_{th_Drv} and a fixed potential applied to the source electrode of the driving transistor is V_{ss} , a voltage that is written to the gate electrode

19

of the driving transistor in a conduction state of the switching transistor is lower than $(V_{th\_Drv}+V_{ss})$.

[8] The display device according to [7], wherein a voltage that is written to the gate electrode of the driving transistor in a conduction state of the switching transistor is lower than a reference voltage that is used when a threshold voltage is corrected.

[9] The display device according to [8], wherein the driving unit writes the reference voltage that is used when a threshold voltage is corrected and a voltage lower than the reference voltage to the gate electrode of the driving transistor via the writing transistor.

[10] The display device according to any one of [2] to [4], wherein, when a threshold voltage of the writing transistor is V_{th_WS} , the threshold voltage of the driving transistor is V_{th_Drv} and the fixed potential applied to a source electrode of the driving transistor is V_{ss} , a voltage causing the writing transistor to enter a non-conduction state is set to be lower than $(V_{th\_WS}+V_{th\_Drv}+V_{ss})$, and the driving unit applies the fixed potential to the source electrode of the driving transistor via the switching transistor before writing the reference voltage that is used when a threshold voltage is corrected to the gate electrode of the driving transistor.

[11] A method of driving a display device in which pixels are arranged, each pixel including a light emitting unit, a writing transistor that writes a video signal, a driving transistor that drives the light emitting unit based on the video signal written by the writing transistor, and a switching transistor that applies a fixed potential to one terminal of the light emitting unit, wherein a voltage causing the driving transistor to enter a non-conduction state is written to a gate electrode of the driving transistor to cause the light emitting unit to enter a light extinction state in driving the display device.

[12] An electronic apparatus with a display device including: a pixel array unit in which pixels are arranged, each pixel including a light emitting unit, a writing transistor that writes a video signal, a driving transistor that drives the light emitting unit based on the video signal written by the writing transistor, and a switching transistor that applies a fixed potential to one terminal of the light emitting unit; and a driving unit that causes the light emitting unit to enter a light extinction state by writing a voltage causing the driving transistor to enter a non-conduction state to a gate electrode of the driving transistor.

It should be understood by those skilled in the art that various modifications, combinations, sub-combinations and alterations may occur depending on design requirements and other factors insofar as they are within the scope of the appended claims or the equivalents thereof.

What is claimed is:

1. A display device comprising:

a pixel array unit in which pixels are arranged, each pixel including a light emitting unit, a writing transistor that writes a video signal, a driving transistor that drives the light emitting unit based on the video signal written by the writing transistor, and a switching transistor that applies a fixed potential to one terminal of the light emitting unit; and a driving unit that causes the light emitting unit to enter a light extinction state by writing a voltage causing the driving transistor to enter a non-conduction state to a gate electrode of the driving transistor, wherein the driving unit applies a fixed potential to a source electrode of the driving transistor via the switching transistor in a state in which the voltage causing the

20

driving transistor to enter the non-conduction state is written to the gate electrode of the driving transistor.

2. The display device according to claim 1, wherein each pixel of the pixel array unit has a function of correcting a threshold voltage of the driving transistor.

3. The display device according to claim 2, wherein the voltage causing the driving transistor to enter the non-conduction state is a reference voltage that is used when the threshold voltage is corrected.

4. The display device according to claim 2, wherein the driving unit writes the voltage causing the driving transistor to enter the non-conduction state to a holding capacitor.

5. The display device according to claim 2, wherein, when a threshold voltage of the writing transistor is V_{th_WS} , the threshold voltage of the driving transistor is V_{th_Drv} , and the fixed potential applied to a source electrode of the driving transistor is V_{ss} , a voltage causing the writing transistor to enter a non-conduction state is set to be lower than $(V_{th\_WS}+V_{th\_Drv}+V_{ss})$ and

the driving unit applies the fixed potential to the source electrode of the driving transistor via the switching transistor before writing a reference voltage that is used when the threshold voltage of the driving transistor is corrected to the gate electrode of the driving transistor.

6. The display device according to claim 1, wherein the driving unit writes a voltage lower than the voltage causing the driving transistor to enter the non-conduction state to the gate electrode of the driving transistor when the switching transistor is in a conduction state.

7. The display device according to claim 6, wherein, when a threshold voltage of the driving transistor is V_{th_Drv} and the fixed potential applied to the source electrode of the driving transistor is V_{ss} , the voltage that is written to the gate electrode of the driving transistor in the conduction state of the switching transistor is lower than $(V_{th\_Drv}+V_{ss})$.

8. The display device according to claim 7, wherein the voltage that is written to the gate electrode of the driving transistor in the conduction state of the switching transistor is lower than a reference voltage that is used when the threshold voltage of the driving transistor is corrected.

9. The display device according to claim 8, wherein the driving unit writes the reference voltage that is used when the threshold voltage of the driving transistor is corrected and a voltage lower than the reference voltage to the gate electrode of the driving transistor via the writing transistor.

10. A method of driving a display device in which pixels are arranged, each pixel including a light emitting unit, a writing transistor that writes a video signal, a driving transistor that drives the light emitting unit based on the video signal written by the writing transistor, and a switching transistor that applies a fixed potential to one terminal of the light emitting unit, the method comprising:

writing a voltage causing the driving transistor to enter a non-conduction state to a gate electrode of the driving transistor to cause the light emitting unit to enter a light extinction state in driving the display device; and applying the fixed potential to the source electrode of the driving transistor via the switching transistor in a state in which the voltage causing the driving transistor to

enter the non-conduction state is written to the gate electrode of the driving transistor.

11. An electronic apparatus with a display device, the display device comprising:

a pixel array unit in which pixels are arranged, each pixel including a light emitting unit, a writing transistor that writes a video signal, a driving transistor that drives the light emitting unit based on the video signal written by the writing transistor, and a switching transistor that applies a fixed potential to one terminal of the light emitting unit; and

a driving unit that causes the light emitting unit to enter a light extinction state by writing a voltage causing the driving transistor to enter a non-conduction state to a gate electrode of the driving transistor,

wherein the driving unit applies a fixed potential to a source electrode of the driving transistor via the switching transistor in a state in which the voltage causing the driving transistor to enter the non-conduction state is written to the gate electrode of the driving transistor.
